UNITED STATES PATENT OFFICE.

DOCTOR FRANKLIN OLIVER, OF OAKLAND, CALIFORNIA.

EXTENSION-TABLE.

1,134,000.

Specification of Letters Patent. Patented Mar. 30, 1915.

Application filed October 27, 1911, Serial No. 657,015. Renewed November 17, 1914. Serial No. 872,652.

To all whom it may concern:

Be it known that I, DOCTOR FRANKLIN OLIVER, a citizen of the United States, and a resident of Oakland, in the county of Alameda and State of California, have invented a new and Improved Extension-Table, of which the following is a full, clear, and exact description.

The object of the invention is to provide 10 a new and improved extension table having 10 slidable end leaves, and extension leaves at the middle of the table and adapted when not in use to be folded within the table rim, the arrangement permitting of readily moving 15 the extension leaves into extended position flush with the end leaves.

For the purpose mentioned, use is made 20 of extension leaves adapted to move transversely into extended or folded positions and 20 provided with pivots engaging fixed transverse guideways extending in opposite directions to permit of swinging the extension leaves on their pivots and pushing the same into positions one above the other and both 25 below the table top.

A practical embodiment of the invention 30 is represented in the accompanying drawings forming a part of this specification, in which similar characters of reference indicate corresponding parts in all the views.

Figure 1 is a plan view of the extension table with the extension leaves in active position; Fig. 2 is a like view of the same showing the end leaves moved outward prior 35 to moving the extension leaves into folded position; Fig. 3 is a plan view of the extension table with the extension leaves in folded position; Fig. 4 is a sectional side elevation of the extension table on the line 4—4 of Fig. 1; Fig. 5 is a cross section of the same on the line 5—5 of Fig. 1; and Fig. 6 is an enlarged plan view of one of the pivots.

The frame A of the extension table is mounted on a suitable leg or legs B, and on 45 the said frame A are fixed longitudinally-extending slide guideways C engaged by slides D, D and D', D' secured to the under side of the end leaves E and E' to permit of moving the end leaves E, E' outward into 50 an extended position, as shown in Figs. 1, 2 and 4, or inward into a closed position, as shown in Fig. 3. The detail construction of the guideways C and the slides D, D' is similar to the ones used in extension tables as 55 now constructed, so that further description of the same is not deemed necessary.

Extension leaves F, F' are adapted to fit between the end leaves E and E' whenever it is desired to extend the table, or the said extension leaves F, F' are moved transversely into folded position immediately above the frame A and below the end leaves E, E' when the latter are in the closed position shown in Fig. 3. For the purpose mentioned the extension leaves F, F' are provided on the under surface at the sides with longitudinally-extending pivots G, G' engaging pairs of transverse guideways H, H', preferably in the form of grooves formed in the opposite inner faces of transversely-extending rails I attached to the top of the frame A of the table. The guideways H and H' are inclined in opposite directions, as plainly indicated in Fig. 5, and the lower ends of the guideways H' are on a lower 70 level than the lower ends of the guideways H, which latter are provided at their upper ends with horizontal extensions H², as plainly shown in Fig. 5. By reference to Figs. 2 and 4, it will be noticed that the guideways H and H' are arranged in different vertical planes, that is, the guideways H are somewhat deeper 75 than the guideways H' and the upper ends of the latter terminate in the guideways H at or near the junction of the horizontal portions H² with the inclined part of the guideways H. Now by the arrangement described, the extension leaves F and F' can be tilted on their pivots G, G' and pushed transversely so as to cause the pivots G and G' to travel 80 in the guideways H and H'. By having the horizontal extensions H² on the guideways H, the extension leaf F can be drawn outwardly in a transverse direction so as to unlock the adjacent inner tongue and groove 85 edges of the extension leaves F and F' (see dotted lines in Fig. 5), to allow of bringing the extension leaf F' into the position shown in dotted lines prior to pushing the extension leaf F' downward into a lowermost or 90 a folded position immediately on top of the frame A. After the extension leaf F' is moved into a folded position as described, the extension leaf is pushed inward so that its pivots G travel along the horizontal portions H² of the guideways H to finally travel 95 down the latter to allow of folding the extension leaf F on top of the extension leaf F' and below the level of the end leaves E and E'. Thus after the extension leaves F and F' have been folded the end leaves E 100 and E' are pushed toward each other into a 105

closed position, as shown in Fig. 3, to cover up the extension leaves F and F'. When it is desired to extend the table, the end leaves E and E' are pulled apart, and then the extension leaf F is drawn upward and outward to the position shown in dotted lines in Fig. 5, to permit of drawing out the other extension leaf F' until the extension leaf F' is in raised position, and then the extension leaf F is pushed toward the extension leaf F' to interlock the opposite edges by their interlocking tongue and groove. In practice, the end leaves E and E' are pushed out farther than the width of the extension leaves F, F' (see Fig. 2), so as to permit of conveniently manipulating the extension leaves F and F' when folding the same or extending the same as above described. After the leaves F and F' are in extended position, the end leaves E and E' are pushed toward each other until their inner edges abut against the side edges of the extension leaves F and F', as shown in Figs. 1 and 4.

Each of the pivots G and G' is preferably formed of a single piece of metal having an attaching flat portion G² fastened by screws or other means to the under side of the corresponding extension leaf F or F', and the flat portion G² terminates in a tubular shank G³ provided at its end with a head G⁴, the shank G³ and the head G⁴ fitting the correspondingly-shaped groove formed in the guideway H or H'. Each pivot G is also provided with a keeper G⁵ in the form of an opening formed at the bent portion G⁶ connecting the flat portion G² with the tubular portion G³, and the said keeper G⁵ is adapted to be engaged by a pin J secured to the under side of the corresponding leaf E or E'. By reference to Fig. 2 it will be seen that the pins J project beyond the inner edges of the end leaves and are in alinement with the corresponding pivots G, G' so that when the end leaves E, E' are moved into closed position at the time the extension leaves F and F' are in raised and extended position, then the said pins J enter the keepers G⁵ thus interlocking the end leaves E and E' with the extension leaves F and F', to securely hold the end leaves and the extension leaves firmly in extended and flush position one relative to the other, as will be readily understood by reference to Figs. 1 and 4.

The extension table shown and described is very simple and durable in construction and composed of comparatively few parts, not liable easily to get out of order.

Having thus described my invention, I claim as new and desire to secure by Letters Patent:—

1. An extension table comprising a table frame and leaves slidably mounted on the said table frame to slide toward or from each other in a lengthwise direction, pairs

of transverse guideways fixed on the table frame and inclined in opposite directions, the said guideways being of different depth, extension leaves adapted to move transversely into extended position between the end leaves and flush therewith or into a folded position one above the other and both below the end leaves, and pivots on the sides of the said extension leaves and of different lengths for engaging the said guideways of corresponding depth. 70 75

2. An extension table, comprising a table frame and leaves slidably mounted on the said table frame to slide toward or from each other in a lengthwise direction, pairs of transverse guideways fixed on the table frame and inclined in opposite directions, one pair of guideways being arranged in a different vertical plane and terminating at a lower level than the other guideways, 80 85 the said guideways being of different depth, extension leaves adapted to move transversely into extended position between the end leaves and flush therewith or into a folded position one above the other and both below the end leaves, and pivots on the sides of the said extension leaves and of different lengths for engaging the said guideways of corresponding depth. 90 95

3. An extension table, comprising a table frame and leaves slidably mounted on the said table frame to slide toward or from each other in a lengthwise direction, pairs of transverse guideways fixed on the table frame and inclined in opposite directions, 100 the guideways of one pair having a horizontal outward extension beginning approximately at the upper ends of the guideways of the other pair of guideways, and the said guideways of one pair being of a 105 greater depth than the guideways of the other pair of guideways, extension leaves adapted to move transversely into extended position between the end leaves and flush therewith or into a folded position one above 110 the other and both below the end leaves, and pivots on the sides of the said extension leaves and of different lengths for engaging the said guideways of corresponding depth. 115

4. An extension table, comprising a table frame, end leaves slidably mounted on the said table frame and provided with retaining pins projecting longitudinally beyond the inner opposite edges of the end leaves, 120 pairs of transverse guideways fixed on the table frame, extension leaves adapted to move transversely into extended position between the end leaves and flush therewith, and pivots on the sides of the extension leaves and engaging the said guideways, the said pivots having keepers for engagement by the said retaining pins at the time the parts are in an extended position. 125

5. An extension table, comprising a table 130

frame, end leaves slidably mounted on the said table frame and provided with retaining pins projecting longitudinally beyond the inner opposite edges of the end leaves, 5 pairs of transverse guideways fixed on the table frame, extension leaves adapted to move transversely into extended position between the end leaves and flush therewith, and pivots each formed of a single piece of metal having an attaching flat portion secured to the under side of the corresponding extension leaf, the flat portion connecting by a bent portion with a tubular shank hav-

ing a head, the shank and head engaging the said guideways and the said bent portion having an opening forming a keeper in alignment with and adapted to be engaged by a corresponding retaining pin at the time the parts are in extended position. 15

In testimony whereof I have signed my 20 name to this specification in the presence of two subscribing witnesses.

DOCTOR FRANKLIN OLIVER.
